DESIGN FOR A BOTTLE

George H. Covert, Cleveland Heights, Ohio

Application October 21, 1936, Serial No. 65,396

Term of patent 14 years

To all whom it may concern:

Be it known that I, George H. Covert, a citizen of the United States, residing at Cleveland Heights, in the county of Cuyahoga and State of Ohio, have invented a new, original, and ornamental Design for a Bottle, of which the following is a specification, reference being had to the accompanying drawing, forming part thereof, in which

Fig. 1 is a front elevational view of the article, showing my new design and,

Fig. 2 is a side elevational view thereof.

The sides of the bottle opposite to those illustrated in Figs. 1 and 2 are, respectively, substantially identical therewith, and there is a middle belt around the bottle containing alternately and symmetrically arranged ribs and grooves.

I claim:

The ornamental design for a bottle substantially as shown and described.

GEORGE H. COVERT.
